SPACE HEATER

Andrew L. Alger, Chicago, Ill., assignor to The Siegler Corporation, Centralia, Ill., a corporation of Delaware

Filed Nov. 12, 1959, Ser. No. 58,312

Term of patent 14 years

(Cl. D81—19)

Figure 1 is a plan view of a space heater showing my new design;

Figure 2 is a perspective view; and

Figure 3 is a side view thereof.

The rear of the space heater is plain aside from a conventional stovepipe outlet.

I claim:

The ornamental design for a space heater, substantially as shown and described.
